UNITED STATES PATENT OFFICE.

SAMUEL SILBERSTEIN, OF PITTSBURG, PENNSYLVANIA.

DESIGN FOR AN EAVES-TROUGH.

SPECIFICATION forming part of Design No. 23,247, dated May 1, 1894.

Application filed January 5, 1894. Serial No. 495,872. Term of patent 7 years.

To all whom it may concern:

Be it known that I, SAMUEL SILBERSTEIN, a citizen of the United States, residing at Pittsburg, in the county of Allegheny and State of Pennsylvania, have invented or discovered certain new and useful Improvements in a Design for Eaves-Troughs, of which improvements the following is a specification.

The design described herein relates to eaves troughs.

In the accompanying drawings forming a part of this specification, Figure 1 is an end elevation of my design for eaves troughs, and Fig. 2 is a side elevation of the same.

The leading feature of my design consists

in longitudinal corrugations and curls along the edges of the trough.

As shown in the drawings, the eaves trough is longitudinally corrugated as at 1, and the edges are curled as at 2.

I claim herein as my invention--

The design for eaves troughs substantially as herein shown and described.

In testimony whereof I have hereunto set my hand.

SAMUEL SILBERSTEIN.
